UNITED STATES PATENT OFFICE.

OSCAR A. DE LONG, OF NEW YORK, N. Y.

DESIGN FOR A BUTTON AND THREAD CARD.

SPECIFICATION forming part of Design No. 23,134, dated March 20, 1894.

Application filed February 12, 1894. Serial No. 499,972. Term of patent 3 $\frac{1}{4}$ years.

To all whom it may concern:

Be it known that I, OSCAR A. DE LONG, a citizen of the United States, residing at New York, in the county of New York, State of New York, have produced a new and original 5 Design for a Button and Thread Card, of which the following is a specification.

This invention relates to a new design for a button and thread card as shown in the accompanying drawing which is a representation of the article. The card A is approximately rectangular shaped, having a long narrow panel *a* at one end and an approximately rectangular shaped panel *b* at the opposite end which is sub-divided by vertical and horizontal lines into squares D. In the middle of these squares D are punctures *d*. Notches *f* are formed in the edges of the card in coincident relation opposite the space between 15 the two panels *a* and *b*. These notches are 20 inversely curved and of corresponding depth

and length, being formed on the arc of a circle whose radius is equal.

The essential feature of the design is an approximately rectangular shaped card having 25 a narrow panel at one end, an approximately rectangular shaped panel at the opposite end subdivided into squares by vertical and horizontal lines, and having punctures in the said squares, and having notches in the edges opposite the space between the said two panels. 30

Having thus described my invention, what I claim, and desire to secure by Letters Patent, is—

The design for a button and thread card 35 substantially as herein shown and described.

In testimony whereof I affix my signature in presence of two witnesses.

OSCAR A. DE LONG.
